Arthur Phelps Warren

UNITED STATES PATENT OFFICE.

ALFONSO A. BANKS, OF NEW YORK, N. Y.

TOWEL RACK.

Application filed February 12, 1921. Serial No. 444,565.

To all whom it may concern:

Be it known that I, ALFONSO A. BANKS, a citizen of the United States, and resident of borough of Manhattan, county of New York, and State of New York, have invented certain new and useful Improvements in Towel Racks.

This invention relates to improvements in towle racks and has for its principal object 10 to provide a device which when not in use may be folded against a wall in order to occupy a minimum amount of space.

Another object of the invention is to provide a device which may be moved into its 15 folded position without necessitating the removal of the contents of the rack.

A further object of the invention is to provide a device which may be readily constructed of wire or similar material.

With these and other objects in view the invention consists of a novel construuation, combination and arrangement of parts which will be fully set forth in the following specification, claimed and illustrated in 25 the accompanying drawings in which:—

Fig. 1, is a perspective view of this improved towel rack illustrating the same extended.

Fig. 2, is a side view of the rack illustrating the same folded and

Fig. 3, is a perspective view of the rack illustrating the same constructed of wire.

Referring to the drawings in detail the numeral 5 designates in its entirety the rack 35 which comprises a frame composed of side bars 6 and 7 connected at their outer ends by a cross bar 8. Similar cross bars 9 may be secured to the side bars' intermediate their ends and it will thus be seen that a 40 rigid frame for supporting towels and the like is provided.

The extreme inner ends of the side bars 6 are turned outwardly as at 10 and are received in openings in the brackets which 45 will be more fully hereinafter described.

The brackets hereinbefore referred to are designated in their entirety by the numeral 11 and each of which comprises a forwardly extending arm 12 formed integrally with 50 a base plate 13. As illustrated in the draw-

ings these arms are provided with openings 14 for the reception of the outturned portions 10 of the side bars 6 and formed integrally with the arms 12 at their extreme outer ends are ears 15 forming rests upon 55 which the under sides of the bars 6 impinge when the rack is in extended position.

In the modified form of the device illustrated in Fig. 3, the rack is designated in its entirety by the numeral 16 and comprises a 60 pair of side bars 17 and 18 the outer ends of which are connected by a transversely extending bar 19. Similar transveresly extending bars 20 are arranged intermediate the ends of the bars 16 and the extreme inner ends of the bars 17 and 18 are turned 65 outwardly to form trunnions 21.

The bracket used in connection with the wire structure above described consists of a substantially U-shaped frame 22 provided 70 intermediate the ends of its arms with loops 23 forming bearings to receive the trunnions 21 and the extreme inner ends of said arms are upturned as at 24 and provided with 75 eyes 25 for the reception of suitable attaching screws 26.

In use it will be seen that a towel or similar article may be hung on any of the transversely extending bars of either device and when it is desired to fold the device out of 80 extended position, it may be thrown into the position illustrated in Fig. 2 without requiring the removal of the article supported thereon.

While in the foregoing there has been 85 shown and described the preferred embodiment of this invention, it is to be understood that certain minor changes in the details of construction, combination and arrangement of parts may be resorted to 90 without departing from the spirit and scope of the invention as claimed.

What is claimed is:—

A towel rack comprising a bar and projection therefrom forming a U-shaped wire 95 frame, said frame having upturned portions, the ends of which are unjoined and having loops formed integral therein to receive screws and the other portions of which are adapted to abut against the wall, loops 100

formed in the arms of said frame between the bar and the wall abutting portions, a U-shaped towel supporting frame adapted to rest upon said bar, trunnions formed in the arms of said towel supporting frame and adapted to be engaged in said last mentioned loops, said towel supporting frame being

adapted to be swung up against the wall and a bar member extending across said towel supporting frame and adapted to have fixed relation therewith.

Signed at the city, county and State of New York, this 7th day of February, 1921.

ALFONSO A. BANKS.
